UNITED STATES PATENT OFFICE.

KENNEDY PARK, OF CAMBRIDGEPORT, MASSACHUSETTS.

APPARATUS FOR FORMING SERPENTINE HOLLOW BODIES.

SPECIFICATION forming part of Letters Patent No. 727,830, dated May 12, 1903.

Application filed April 17, 1902. Serial No. 103,361. (No model.)

To all whom it may concern:

Be it known that I, KENNEDY PARK, of Cambridgeport, in the county of Middlesex and State of Massachusetts, have invented certain new and useful Improvements in Apparatus for Forming Serpentine Hollow Bodies, of which the following is a specification.

This invention relates to the manufacture of serpentine headers which are rectangular in cross-section and flat on two opposite sides, the other two sides being serpentine. Headers of this character are used in sectional steam-boilers wherein the serpentine sides are nested together.

Serpentine headers are commonly made by applying pressure to a length of wrought-iron pipe or tubing in such manner as to change the form of its cross-section and impart to it the flat and serpentine sides above referred to, the process being applied by two pairs of dies, the members of one pair being flat and the members of the other pair corrugated. Heretofore the tube has been internally supported against the pressure of the dies by a mandrel formed to impart the desired shape to the interior of the header. It is impossible, however, to remove the mandrel bodily from the formed header, it being customary to make the mandrel in separable sections, so that the mandrel can be dissected and removed piecemeal from the header after the forming operation. The construction of a sectional mandrel is expensive and much time is required in separating and reassembling its parts.

My invention has for its object, first, to dispense with a sectional mandrel or other rigid internal support and to provide instead a yielding internal support adapted to conform accurately to the external dies and to be readily inserted in and removed from the header.

The invention also has for its object to provide certain improvements in the form and construction of the dies and in the means for operating the same.

The invention consists in the improvements which I will now proceed to describe and claim.

Of the accompanying drawings, forming a part of this specification, Figure 1 represents a top plan view of an apparatus embodying

my invention, the parts of the apparatus being shown in section. Fig. 2 represents a section on the line 2 2 of Fig. 1. Fig. 3 represents a sectional view of a portion of the apparatus on a larger scale. Fig. 4 represents a section on the line 4 4 of Fig. 1. Fig. 5 represents a sectional view of the portion of one of the serpentine dies, showing the same with the crest of its waves diagonally arranged. Fig. 6 represents a face view of the portion of the die shown in Fig. 5. Fig. 7 represents in separate views the tube from which the hollow body is formed. Fig. 8 represents in separate views a complete serpentine header as formed by my improved apparatus, with the exception of the tube-receiving holes, which are formed in the header by a subsequent operation. Fig. 9 represents in separate views the form of serpentine pieces produced by the serpentine die represented in Figs. 5 and 6. Fig. 10 represents a sectional view of the sliding abutment and of the portion of the movable ram member or follower, hereinafter referred to.

The same characters of reference indicate the same parts in all the figures.

On the drawings, *a a* represent die-carriers, which are mounted to rotate or oscillate on fixed centers *b b*, the carriers *a a* being preferably circular, as shown in Fig. 1. Each die-carrier has a serpentine die-face *c*, adapted to act progressively in forming the serpentine sides 2 2 on the serpentine header 3, the said serpentine dies being here shown as segmental and occupying only portions of the peripheries of the die-carriers. At the opposite ends of the serpentine dies are formed flat die-faces *c' c'*, adapted to form the flat portions 4 4 at the ends of the serpentine sides of the header. The blank for the header is a length of wrought iron or steel tubing 1. (Shown in Fig. 7.) Before the forming operation an end piece 5 is welded firmly in the leading end of the tube 1, and a conformable freely-flowing support *d* is placed in the tube, such support, as shown in Figs. 1, 2, and 3, being a mass of loose hardened-steel balls of small size, preferably about three-eighths of an inch in diameter, although the diameter of the balls may be varied to suit the size of the fillets or grooves and the serpentine edges of the header. I do not limit myself, how-

ever, to an internal support composed of balls, as any other suitable internal support which is adapted to be readily poured into and out of the tube and is practically non-compressible, although conformable and extensible, so it will afford an adequate internal support for the tube against the pressure of the dies, may be used. It is obvious that a suitable liquid might be employed as the flowing internal support, although for various reasons I prefer the form of support first described. The die-carriers are provided with abutment-pieces c^2 c^2 , arranged to meet and form an abutment for the leading end of the tube 1 when the latter is first presented at the nip of the serpentine dies. The dies are moved in unison on their centers b by means hereinafter described and in the direction indicated by the arrows in Figs. 1 and 3, the serpentine dies c being thus caused to act on the tube progressively and form the two serpentine sides 2 2. At the same time the two pairs of side dies c^3 c^3 , formed on the die-carriers at opposite sides of the serpentine dies, coöperate in forming the flat sides 3 of the header, the acting faces of the said dies c^3 c^3 being the inner sides of flanges formed on or attached to the die-carriers and projecting outward from the serpentine dies c . It will be seen that as the sides of the tube are indented by the serpentine dies the metal displaced is caused to fit closely against the side dies and is carried rearwardly, elongating the tube.

The conformable internal support d is held at its front end by the plug 5 and is yieldingly supported at its rear end by an abutment e , which has a sliding fit in the tube 1 and bears against the rear end of the support d . Said abutment is given a forward yielding movement, so that it follows the general endwise movement of the tube caused by the rotation of the die-carriers and at the same time yields to the extent required by the extension or elongation of the tube and of the support d . I have here shown as the preferred means for applying the described yielding pressure to the abutment e a hydraulic ram, the piston f of which has a rod or follower f' , arranged to engage the abutment e and force the same toward the nip of the dies. The cylinder f^2 of the ram has suitable inlet and outlet passages f^3 f^4 , a suitable valve mechanism being provided for admitting water under pressure first into one and then into the opposite end of the cylinder, water being admitted through the passage f^3 during the forming operation and pressing the piston toward the nip of the dies.

After the forming operation and when it is desired to withdraw the piston or move it from the nip of the dies the water is admitted through the passage f^4 and allowed to escape through the passage f^3 . The described yielding movement of the abutment e is or may be provided for by means of a pressure-

valve g , located in an outlet-pipe g' at one end of the ram-cylinder, said valve being set or adjusted to the pressure required to bend or indent the metal of the tube.

70

The die-carriers a are moved in unison by suitable means, the extent of movement being sufficient to cause the serpentine dies to act on the entire length of the tube and deliver the same completed so far as the form of its sides 2 2 and 3 3 are concerned at the delivering side of the carriers. I have here shown as the means for operating the die-carriers a hydraulic ram, the piston h of which is connected by its rod h' with a cross-head i , the latter being connected by rods j with the die-carriers. The cross-head i is adapted to slide on guides i' on the base k , said guides directing the movement of the cross-head. Water under pressure is submitted to and allowed to escape from the ram-cylinder h^2 to passages h^3 h^4 , a suitable valve mechanism being employed to reverse the direction of the water and of the movement of the piston h . The extent of the movement imparted to the die-carriers is regulated by the said valve mechanism controlled by an attendant.

80

The parts above described are mounted upon a suitable supporting-base k . The centers b on which the die-carriers move are preferably adjustable on said base toward and from each other to compensate for the variations in the thickness of the walls of the headers. Each center b is here shown as affixed to a dovetail slide b' , (see Fig. 4,) fitted in a dovetail groove in the base k and adjustably secured to the base by suitable means.

95

m represents a guide adapted to direct the movement of the tube or blank 1 toward the nip of the roll of the die, said guide being composed of two parallel upright flanges on the base k .

100

If desired, each carrier a may have more than one serpentine die. I have here shown a second serpentine die c^4 , formed on each die-carrier. The dies c^4 may be formed with the crest of their waves extending obliquely relative to the axis of the die-carrier instead of parallel to that axis. The dies c^4 are thus adapted to form serpentine sides with obliquely-extending waves, as shown in Fig. 9. To make the serpentine dies c^4 operative, the rods j are to be disconnected from the points to which they are shown as connected in Fig. 1 and engaged with the die-carriers at the points j' . One or more of the waves or fillets of each serpentine die may be detachable, as indicated by dotted lines in Fig. 1, to vary the length of the die.

110

In Fig. 1 I have shown the serpentine dies as occupying about one-half of the peripheries of the die-carriers, the remaining portion of the peripheries being occupied by segmental die-faces c^5 c^5 , which are formed to coöperate with the side dies c^3 in forming two flat sides or a box-shaped header which is not serpentine. When the die-faces c^5 are to be used,

115

120

125

130

the connecting-rods *j* are engaged with the die-carriers at the points *j*² *j*³.

5 *o o* represent holding-down flanges, which are affixed to the base *h*, and projecting over the lower flanges *c*³ of the die-carriers to prevent the carriers from being tipped.

10 The abutment *e* is preferably flexible, so that when the form of the portion of the tube immediately surrounding it begins to change, the abutment will conform to the changed 15 shape of the tube. The abutment is preferably made in the form of a hollow cone of sheet metal, its larger end fitting the interior of the tube and changing in shape as the portion of the tube surrounding it changes. The smaller end of the abutment engages a cup formed in the outer end of the rod or follower *f*.

20 The operation of the described apparatus is as follows: The die-carriers being adjusted, so that the abutments *c*² *c*³ are somewhat at the left to the point of closest approach of the roll as the apparatus is viewed in Fig. 1, the tube or blank 1, with its forward end 25 closed by the plug 5 and with the conformable inner support *d* in position, is placed against the abutments *c*² in the guide *m*. The sliding abutment *e* is placed in position in the tube directly after the introduction of the filling *d* and serves to retain said filling in place 30 while the parts are being attached. The rod or follower *f*' of the abutment-pressing ram is then engaged with the abutment *e*. The operator then admits water under pressure 35 simultaneously to the cylinders of the two rams, causing the die-carriers to rotate, thus drawing the tube forward and commencing to form it into a header, the rod or follower *f*' and the abutment *e* at the same time moving forward at a rate which is determined by 40 the elongation of the tube or blank by the action of the die. The "forming" or action progresses until the entire blank has been formed and converted into a partially-complete 45 header, which is ejected by the continuous movement of the die-carriers in the direction indicated. After the ejection of the formed header the operator reverses the valve mechanism and causes the pistons *f* and *h* to 50 move in the opposite direction, thus moving the die-carriers back to their starting position and withdrawing the rod or follower *f*' from the space within the die which is to be 55 occupied by the next blank. In order to secure the best results, the blank should be heated prior to the forming operation to a suitable degree to enable it to be easily worked.

Having thus explained the nature of the invention and described a way of constructing 60 and using the same, although without attempting to set forth all of the forms in which it may be made or all of the modes of its use, I declare that what I claim is—

1. An apparatus of the character described 65 comprising dies adapted to externally form a serpentine hollow body, a conformable flowing support for the interior of said body, and

a yielding abutment opposing the extension of said support.

2. An apparatus of the character described 70 comprising dies adapted to externally form a serpentine hollow body, a conformable flowing support for the interior of said body, an abutment having a sliding fit in said body and bearing on the rear end of said support, and 75 means for yieldingly opposing outward movement of said abutment.

3. An apparatus of the character described 80 comprising dies adapted to externally form a serpentine hollow body, a conformable flowing support for the interior of said body, an abutment having a sliding fit in said body and bearing on the rear end of said support, and a hydraulic ram, the piston of which is connected with said abutment. 85

4. An apparatus of the character described 90 comprising two die-carriers mounted to rotate or oscillate on fixed centers, and provided with progressively-acting serpentine dies arranged to form serpentine sides on a hollow body, and with progressively-acting side dies arranged to form said body between the serpentine sides, means for moving said carriers in unison, a conformable flowing support for the interior of said body, and means for advancing said support in the direction of movement of the said body. 95

5. An apparatus of the character described 100 comprising two rotary or oscillatory circular die-carriers provided with flanges, the inner sides of which constitute side die-faces and with peripheral serpentine die-faces between said flanges, means for moving said carriers in unison, a conformable flowing support for the interior of said body, and means for advancing said support in the direction of movement of the said body. 105

6. An apparatus of the character described 110 comprising two rotary or oscillatory circular die-carriers provided with side die-faces, peripheral serpentine die-faces between said side faces, and abutments for the leading end of the body to be formed.

7. An apparatus of the character described 115 comprising two rotary or oscillatory circular die-carriers provided with side die-faces, segmental serpentine die-faces between said side faces, and flat die-faces at the opposite ends of the said segmental faces.

8. An apparatus of the character described 120 comprising two rotary oscillatory die-holders having progressively-operating serpentine and side dies, and carrier-operating means comprising a hydraulic ram and connections between the piston of said ram and the carriers. 125

9. An apparatus of the character described 130 comprising opposed oscillatory die-carriers having segmental serpentine dies and side dies at opposite sides of said serpentine dies, means for moving said carriers in unison, a tube or blank guide at the receiving side of the carriers, a conformable flowing internal support for a tube or blank in said guide, a

sliding abutment for the rear end of said support, and means for yieldingly supporting and impelling the abutment.

10. An apparatus of the character described comprising opposed oscillatory die-carriers having segmental serpentine dies and side dies at opposite sides of said serpentine dies, a tube-guide at the receiving side of said carriers, a hydraulic ram arranged with its movable member in line with a tube in said guide, so that said member can enter and follow said tube, an abutment held by the movable ram member at the outer end of a conformable flowing-support in said tube, and another hydraulic ram having its movable member connected with said carriers to move the same in unison.

11. An apparatus of the character described comprising opposed oscillatory die-carriers

having segmental serpentine dies and side dies at opposite sides of said serpentine dies, a tube-guide at the receiving side of said carriers, a hydraulic ram arranged with its movable member in line with a tube in said guide, so that said member can enter and follow said tube, an abutment held by the movable ram member at the outer end of a conformable flowing support in said tube, another hydraulic ram, connections between the piston of said ram and the carriers, said connections including a cross-head, and fixed guides for said cross-head.

In testimony whereof I have affixed my signature in presence of two witnesses.

KENNEDY PARK.
